United States Patent Office

Des. 185,475
Patented June 9, 1959

185,475

CRUCIBLE

Charles A. Weller, Bloomfield, N.J., assignor to Baker & Company, Incorporated, Newark, N.J., a corporation of New Jersey

Application October 16, 1956, Serial No. 43,374

Term of patent 14 years

(Cl. D16—1)

Fig. 1.

Fig. 2.

Figure 1 is an elevational view; and

Figure 2 is a perspective view of a crucible, showing my new design.

The side of the crucible not shown is the same as the side shown.

I claim:

The ornamental design for a crucible, as shown and described.
